INSOLE MARKING DEVICES

Alfred S. Clark, Beverly, Mass., assignor to United Shoe Machinery Corporation, Flemington, N. J., a corporation of New Jersey

Application December 18, 1951, Serial No. 262,227

1 Claim. (Cl. 101—41)

This invention relates to machines for operating upon shoe insoles and it is herein disclosed as embodied in a machine for making reference marks upon an insole to establish the location of the heel, breast line as a guide for the performance of subsequent operations. For examples of machines having breast line marking devices, reference may be had to United States Letters Patent No. 1,113,544 granted October 13, 1914, in the name of Miller Cook, Jr., and also to United States Letters Patent No. 2,699,110, granted January 11, 1955, upon my application; and reference may be had also to my copending application Serial No. 250,762 filed October 10, 1951.

Machines of the type disclosed in said Letters Patent and copending application are known as lip cutting and scoring machines and are usually equipped with lip cutting knives, centering gages, and devices for impressing size and width marks upon a sole. In order to simplify the following disclosure, any showing of such knives and centering gages will be omitted herefrom.

In some types of work it is desirable to provide reference marks indicating the position of the breast line not only upon the grain surface of the insole but also upon the flesh surface. It is customary to mark the breast line on the grain surface by indentations known as score marks; if, however, indentations are made in the flesh surface they are apt to be lost to sight in the loose texture of the leather, or at least to be too inconspicuous to be of help in guiding subsequent operations.

An object of the invention is to provide means for applying a conspicuous mark to the flesh surface of an insole and a suitable mark in register therewith on the grain surface to establish the location of the heel, breast line. The mark on the flesh surface is preferably a plainly visible ink mark, and conveniently a composite mark having spaced portions; and the mark on the grain surface is preferably an indentation or line of indentations, known as a score mark, extending transversely of the insole. The two marks should be in register with each other longitudinally of the insole, i. e., the transverse (with respect to the insole) center line of the composite ink mark and the corresponding center line of the score mark should coincide, except for the separation occasioned by the thickness of the insole; thus, if the two transverse center lines of the marks are at equal distances from the toe end of the insole, or from the heel end (by which the position of the insole is usually gaged), the two marks will be in register longitudinally of the insole. The illustrated machine is arranged for presentation of the insole grain surface down; the indentations are applied to the under or grain surface and the more conspicuous ink mark to the upper or flesh surface.

In accordance with the above stated object, a feature of the invention resides in the provision of a work table and a marking tool associated therewith for supporting and marking the under surface of an insole, in combination with a second marking tool and a presser which are engageable with the upper surface of the insole, the presser serving to press the insole directly against the first

2

mentioned marking tool to apply a mark to the under surface of the insole, and the second marking tool having spaced portions which embrace the presser and apply a composite mark to the upper surface in register with the mark on the under surface. The tool which marks the upper or flesh surface, as shown herein, is an ink pad having spaced work-engaging portions on opposite sides of the presser for printing a composite mark.

This and other features of the invention will appear from the following detailed description of an illustrative embodiment of the invention when considered in connection with the accompanying drawings, and will be pointed out in the appended claims.

Referring now to the drawings,

Fig. 1 is a view partly in section and partly in elevation of an illustrative machine embodying the invention;

Fig. 2 is a plan view of a marking device and its supporting block constituting a portion of the machine shown in Fig. 1;

Fig. 3 is a vertical sectional view taken on the line III—III of Fig. 2;

Fig. 4 is a vertical sectional view taken on the line IV—IV of Fig. 2;

Fig. 5 is a bottom plan view of the marking tool shown in Fig. 3;

Fig. 6 is a view of a composite ink mark applied to the flesh surface of an insole by the machine;

Fig. 7 is a view of an indented score mark formed upon the grain surface of the insole in register with the ink mark shown in Fig. 6;

Fig. 8 is an elevational fragmentary view of an ink-marking tool for imprinting an ink mark of different shape;

Fig. 9 is a bottom plan view of the marking tool shown in Fig. 8;

Fig. 10 is a view of an ink mark imprinted by the tool shown in Figs. 8 and 9, and

Fig. 11 is a view of the indented mark formed on the grain surface of the insole in register with the ink mark shown in Fig. 10.

Referring to Fig. 1, the work-engaging instrumentalities of the illustrated machine which comprise the subject matter of the present invention consist of a work table 20, a marking device 22 and an indenting tool 24. Other work-engaging instrumentalities which may be included in the machine consist of a heel end gage 26, a size marking die 28, a width marking die 30, and pressers 32 and 34 cooperating with the dies 28 and 30 respectively. Although machines of the type illustrated herein are commonly equipped with lip cutting knives and coordinated centering gages, any showing of such members has been omitted from the present disclosure in the interest of clarity.

The marking device 22 and the pressers 32 and 34 are carried by a head or carrier 36 which constitutes the forward end portion of a rocking frame 38 pivotally supported by trunnions 40 journaled in the frame of the machine. Trunnioned in the rear portion of the frame 38 is a block 42 through which is threaded a rod 44. Rotatably attached to lower end of the rod 44 is a bracket 46 which is integral with an eccentric strap 48. In driving engagement with the strap 48 is an eccentric 49 on a shaft 50 which is journaled in bearings in the machine frame and driven by any suitable source of power. Secured on the upper end of the rod 44 is a knob 52 to facilitate turning for the purpose of adjusting the rocking frame 38 about its trunnions 40. A winged nut 54 locks the rocking frame 38 in adjusted position on the rod 44.

The work table 20 consists of the top of a box-like frame or housing 56. Fitted into a transverse recess in the work table 20 is a bar 58 having extending upwardly therefrom above the upper surface of the work table 20

a plurality of teeth for marking a line of indentations upon the under surface of a work piece. These teeth, together with bar 58, constitute the indenting tool 24.

The heel end gage 26 can be adjusted forwardly and rearwardly of the machine by a cam 60 secured upon a shaft 62 which is turned by a hand wheel 64. Secured upon the shaft 62 is a wheel 66 which carries a plurality of the size marking dies 28. The width marking dies 30 are carried by a bar 68 which is mounted for transverse sliding movement in a recess formed in the work table 20. The arrangement just described for adjusting the heel end gage and for bringing selected width and size marking dies into operative position are well known in the art.

The marking device 22, as shown in Figs. 2 to 5, inclusive, comprises a cylindrical metal holder or tube 70 in the lower portion of which is formed a bore 72 of large diameter for holding an ink marker 74 consisting of a cylindrical plug of absorbent felt for holding a supply of ink. The upper portion of the holder or tube 70 is drilled and tapped for threaded engagement with a presser rod 76 extending axially through the holder 70. A lock nut 78 secures the rod 76 in a desired position of adjustment in the holder 70. The ink marker 74, which has a central opening to receive the rod 76, extends down through the lower open end of the holder 70, and tapers to a squared-off lower end portion 80 shaped to print a composite ink mark substantially in the form of a discontinuous rectangle, as shown in Fig. 6. It will be noted that the presser 76, at its lower or operative end, is positioned between, or is embraced by, the spaced work-engaging portions of the ink marker 74. A longitudinal duct 82 extends through the holder 70 from the top of the bore 72 to the upper end of the holder 70 and serves as a vent to permit the escape of air, thus expediting the absorption by the marker 74 of ink from a container (not shown).

Clamped upon the upper end of the holder 70 by a screw 84 is a split block 86. Threaded down through the block 86 is a screw 88, the lower end of which engages the upper surface of the head 36 to determine the desired position of heightwise adjustment of the holder 70. A pin 90 extending up from the head 36 is embraced by a pair of ears on the block 86 to determine the rotational position of the block 86 about the axis of the holder 70. Before the clamping screw 84 is tightened, the holder 70 should be turned to bring the long axis of the rectangular printing surface 80 into transverse relation to the machine. The felt ink marker 74 fits tightly enough within the bore 72 to prevent its undesired rotation. A setscrew 92 (Fig. 1) secures the holder 70 in the position determined by the screw 88 and the pin 90. When the head 36 descends to bring the marking surface 80 and the rod 76 into contact with a workpiece, the point of intersection of the axis of the holder 70 with the surface of the workpiece is directly over the line of the indenting teeth 24.

In the operation of the machine as so far described, the depression of the head 36 will bring the operative end 80 of the ink marker 74 down to imprint upon the flesh surface of an insole S the composite mark shown in Fig. 6 while, at the same time, the rod 76 will press the insole against the teeth 24 of the score marking tool 58 to im-

press into the grain surface of the insole S the indented line, comprising two indentations, shown in Fig. 7. The transverse center line of the ink mark shown in Fig. 6 is indicated by a dot-dash line X—X, and the transverse center line of the indentations shown in Fig. 7 is indicated by the dot-dash line X'—X'. On the insole S, the line X—X will be directly over the line X'—X', and separated therefrom only by the thickness of the material. It is evident from the above description, or from an inspection of Fig. 1, that the ink mark shown in Fig. 6 and the indented line shown in Fig. 7 will be in register with each other longitudinally of the insole.

In Figs. 8 and 9 are shown an ink marker 94 having a lower end portion different in shape from that of the ink marker 74. The ink marker 94 terminates at its lower end in two flat-surfaced ridges 96 which imprint upon the flesh surface of an insole S the composite mark shown in Fig. 10, while the rod 76 presses the insole against the teeth 30 to form in the grain surface a line of indentations as shown in Fig. 11. The transverse center lines of the marks shown on Figs. 10 and 11 are indicated by the dot-dash lines Y—Y and Y'—Y' respectively. On the insole S, these lines will be separated only by the thickness of the material, and will therefore be register with each other longitudinally of the insole.

Having described my invention, what I claim as new and desire to secure by Letters Patent of the United States is:

In a machine for operating upon shoe soles, a work table for supporting a sole by engagement with the under surface thereof, an indenting tool supported in fixed relation to the work table and extending above the sole supporting surface thereof for engagement with the under surface of the sole, a tube having an open end, an absorbent felt ink marker carried within the tube for holding a supply of ink and extending from the open end of the tube for engagement with the upper surface of the sole, a presser carried axially within the tube and surrounded by the ink marker, said presser extending from the open end of the tube for engagement with the upper surface of the sole at a locality between and adjacent to localities engageable with the ink marker, a carrier for the tube, and operating means for depressing the carrier to bring the ink marker and the presser down upon the upper surface of the sole to cause the presser to press the sole directly against the indenting tool and thereby to cause an indentation to be impressed into the under surface of the sole, said operating means serving at the same time to cause the ink marker to print upon the upper surface of the sole a mark which is in register with the indentation on the under surface.
